UNITED STATES PATENT OFFICE.

JOHN H. LEWIS, OF CHICAGO, ILLINOIS, ASSIGNOR OF ONE-HALF TO LOUIS G. KUNZER,
OF OAK PARK, ILLINOIS.

LOCOMOTIVE NOISELESS SMOKE-CONSUMER.

1,273,885.

Specification of Letters Patent.

Patented July 30, 1918.

Application filed July 25, 1914. Serial No. 853,006.

To all whom it may concern:

Be it known that I, JOHN H. LEWIS, a citizen of the United States, residing at Chicago, in the county of Cook and State of Illinois, have invented a certain new and useful Improvement in Locomotive Noiseless Smoke-Consumers, of which the following is a full, clear, concise, and exact description, reference being had to the accompanying drawings, forming a part of this specification.

This invention relates to improvements in locomotive noiseless smoke consumers.

As is well known, engineers and firemen on locomotives have considerable difficulty in conversing with each other in the cab of a locomotive while the same is running, due to the great amount of noise. This makes it practically impossible for the men to hear each other unless they shout and, as will be appreciated, it is extremely desirable that the men be able to converse readily in order to convey directions or orders or information from one to the other. One of the main causes of the great amount of noise is the air injectors at the sides of the firebox which ordinarily consist of a plurality of steam nozzles on each side of the firebox located within a corresponding number of openings or short pipes leading from the atmosphere to the interior of the firebox through which the air is drawn by the suction induced by the steam.

The main object of my invention is to provide an arrangement whereby the above noted difficulties are overcome and so arranged that the efficiency of the air injector is not impaired.

Another and more specific object of my invention is to provide a noiseless smoke consumer so arranged that the intake or intakes for the air are well removed from the firebox.

Another object of the invention is to provide a device of the class above described wherein is employed a muffler or means for deadening or minimizing the noise where the air is taken into the pipe or pipes before forced into the firebox.

The invention furthermore consists in the improvements in the parts and novel combinations of the parts herein shown, described and claimed.

In the drawing forming a part of this specification, Figure 1 is a side elevation of

the locomotive firebox and boiler showing my improvements in connection therewith, parts being broken away to prevent crowding of the drawing. Fig. 2 is an end elevation of the structure shown in Fig. 1, a portion being broken away at one side to more clearly illustrate some of the details of construction. Fig. 3 is an enlarged detail sectional view showing the steam nozzle in the air pipe. Fig. 4 is an enlarged detail sectional view taken substantially on the line 4—4 of Fig. 1. Fig. 5 is an enlarged detail diametrical sectional view of the muffler employed at the intake and Fig. 6 is a sectional view taken substantially on the line 6—6 of Fig. 5.

In said drawing, 10 denotes the boiler and 11 the firebox both of which are or may be of the usual or well known construction. As customary, the firebox is provided with a door or opening 12, inner shell or wall 13 and outer shell or wall 14. The steam line from the boiler is designated by the reference 15 and the same terminates in a T—16 from which lead pipes 17—17, one to each side of the locomotive. The supply of steam to the pipes 17—17 is controlled by a globe valve 180. Inasmuch as the construction on each side of the locomotive is the same, I will only describe that for one side.

On each side, the pipe 17 is extended to a point well forward of the firebox and is fitted with an L 18 to which is secured a short section of pipe or nipple 19 the latter having an L 20 at the bottom from which extends a nozzle 21, the nozzle being pointed toward the firebox and held in position in the T 22 by means of transversely extending pins 23, it being understood that the nipple 19 passes through a nut 24 threaded into the upper side of the T 22. From the T 22 the air pipe line 25 is extended rearwardly and along the side of the firebox, and is provided with a plurality of branch pipes leading to the interior of the firebox. These branch lines or inlets to the firebox lead from a plurality of T's 26 and an L 27 at the end of the pipe 25. Each branch or air inlet to the firebox comprises a cylindrical hollow member 28 threaded at its outer end into the respective T or L 26 or 27 as indicated at 29 and at its inner end each member 28 is provided with a flange 30 which overlaps the flanged end 31 of a bushing 32 extending between the two 110

walls or shells 13 and 14, each bushing 32 being also flanged on its outer end as indicated at 33.

From the opposite side of the T 22, ex-
5 tends a larger air intake pipe 34 which is
bent downwardly as clearly indicated in Fig.
1 and at its outer end has attached thereto
a muffler 35, the latter comprising a cylindri-
cal member having a tortuous air passage 36
10 therein which is formed by means of a plu-
rality of oppositely and alternately arranged
walls or baffles 37—37, the interior of the
muffler 35 being rounded as indicated at 38
opposite the free ends of the walls or baffles
15 37. The two pipe lines 17 and 25 are suit-
ably secured together by clamp plates 39 and
bolts 40 and the T 22 and intake pipe 34 are
suitably secured to the boiler by means of
a hanger 41 attached by a bolt or other suit-
20 able device 42.

In operation, when steam is admitted to
the pipes 17—17 a jet of steam will flow
through each nozzle 21 in the direction indi-
cated by the arrow *a* in Fig. 3 and these
25 steam jets or nozzles induce a current of air
through the intake pipes 34—34 and mufflers
35—35, the air passing through the latter
in the direction indicated by the arrow *b*.
From the T's 22—22 the air is then forced
30 along the pipes 25—25 and through the
branch inlet pipes to the interior of the fire-
box and in this connection it will be ob-
served that there are no openings on the ex-
terior of the fire-box where the air is forced
35 thereinto so that there is no perceptible
noise due to the inrushing mixed air and
steam. Furthermore, the air intake is so

far removed from the firebox, and conse-
quently the cab wherein the engineer and
fireman stand, that the amount of noise is 40
minimized and particularly on account of
the mufflers which deaden or reduce the noise
as the air is drawn from the atmosphere.

Although I have herein shown and de-
scribed what I now consider the preferred 45
embodiment of my improvements, yet the
same is merely illustrative and I contem-
plate all such changes and modifications as
come within the scope of the claim appended
hereto. 50

I claim:—

In a locomotive having the usual fire box
and boiler, the combination with an air pipe
line extending along the outside of the fire
box and boiler, of a muffler at the intake 55
end of said air pipe line, the muffler being
located well forward of the fire box, a steam
nozzle extended into said air pipe line ad-
jacent said muffler, and a plurality of branch
inlet pipes extending from said air pipe 60
line through the side of the fire box and to
the interior of the latter, the passage ways
provided for said branch pipes through the
side wall being sealed, whereby air is drawn
in entirely by and mixed with the steam in 65
the air pipe near the intake end of the latter
and remote from the rear end of the fire box
and the mixed air and steam is injected into
the fire box with a minimum of noise at the
rear end of the fire box.

JOHN H. LEWIS.
